(57) **CLAIM**

We claim the ornamental design for a model vehicle skid pad, as shown and described.

DESCRIPTION

FIG. 1 is an upper, right, rear perspective view of a model vehicle skid pad showing our new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is an upper plan view thereof;

FIG. 7 is a lower plan view thereof; and,

FIG. 8 is an upper, left, front perspective view of the model vehicle skid pad.

In the drawings, the broken lines illustrate portions of the model vehicle skid pad that form no part of the claimed design.

In the drawings, only the left-side of the model vehicle skid pad is shown. The right-side of the model vehicle skid pad is a mirror image of the shown model vehicle skid pad.
